(57) **CLAIM**

The ornamental design for sensor and clamp assembly, substantially as shown and described.

DESCRIPTION

FIG. 1 is a left side perspective view of the assembled sensor and clamp assembly employing my new design; FIG. 2 is a left side view of FIG. 1;

FIG. 3 is an exploded left side view of FIG. 1;

FIG. 4 is a bottom exploded view of FIG. 1;

FIG. 5 is a bottom assembled view of FIG. 1;

FIG. 6 is a top exploded view of FIG. 1;

FIG. 7 is a top assembled view of FIG. 1;

FIG. 8 is a bottom exploded perspective view of FIG. 1;

FIG. 9 is a bottom assembled perspective view of FIG. 1;

FIG. 10 is a front assembled view of FIG. 1; and,

FIG. 11 is a rear assembled view of FIG. 1.

The right side views are not shown but are mirror images of the left side views.
